UNITED STATES PATENT OFFICE.

GEORGE GEISENDORFER, OF UKIAH, CALIFORNIA.

BOTTLE.

No. 900,364.

Specification of Letters Patent.

Patented Oct. 6, 1908.

Application filed November 23, 1907. Serial No. 403,525.

To all whom it may concern:

Be it known that I, GEORGE GEISENDORFER, a citizen of the United States, residing at Ukiah, in the county of Mendocino, State of California, have invented certain new and useful Improvements in Bottles, of which the following is a specification.

This invention relates particularly to original packages provided with means which insure a change in the characteristic appearance of the package upon its first being opened. It is therefore a preventive against the substitution and sale of counterfeit goods in packages which are apparently original. The idea is that no bottle can be sold more than once as an original package. Attempts have been made to accomplish this object by changing the appearance of the package, but so far as I am aware such attempts have been based upon the principle of altering the appearance by fracturing or rupturing the bottle itself, as by weakening the bottle neck at a certain point so that a part of such neck can be broken off and separated by a sharp blow. Such means are believed to be objectionable, if only for the reason that glass must be broken, particles of which may find their way into the bottle; and with such devices there is no certain way of preventing this from happening.

Generally speaking, the present invention comprises the combination with the bottle of an independent sleeve formed of material which can be easily ruptured by force properly applied, and which, when so ruptured, will result in a decided change in the characteristic appearance of the package; and also, and preferably, in providing such a sleeve with self-contained means for rupturing it.

Embodiments of the invention are hereinafter described and are shown in the accompanying drawings, in which:

Figure 1 is a vertical section of the neck of the bottle provided with my device. Fig. 2 is an elevation of the same. Fig. 3 is a top plan. Fig. 4 is a vertical section for the purpose of showing such a bottle neck as that of Fig. 1 with its two parts dissociated. Fig. 5 is a horizontal section on the line $\alpha-\alpha$ of Fig. 1. Fig. 6 is a vertical section of a modified construction. Fig. 7 is an elevation of a sleeve provided with corrugations of a general spiral form, adapted to fit grooves of the same form in the bottle neck. Fig. 8 is an elevation of a similar sleeve provided with separate projections, answering the same purpose of holding such sleeve in the bottle neck.

Throughout the drawing 1 represents a bottle and its neck to which my invention is applied. I refer at first more particularly to Figs. 1 to 5 inclusive, and thereafter describe certain modifications in construction and arrangement.

Fig. 2 shows the external appearance of a bottle forming an original package before such bottle has ever been opened, and containing my invention, the detail construction of which is shown in Fig. 1. The bottle neck in this form is made in two parts 1 and 2 and such parts are joined, connected and secured together by the sleeve 3, the whole neck being slightly contracted by internal tapering toward its middle. This sleeve is composed of some suitable metal such as lead or some other metallic composition which has stiffness enough to act as a connection between the parts, and which is yet soft enough to be easily ruptured when force is properly applied to it for that purpose. There are many compositions known in the arts which are suitable for my purpose, and I do not limit myself to any special material. This sleeve is embedded in the two part neck of the bottle in any suitable manner although preferably it is done when the bottle is made the glass being molded, blown or otherwise formed around the sleeve. The sleeve is preferably stiffened by a flange 4 which may be rounded or otherwise shaped to impart a neat finish to the bottle in the manner shown in Fig. 2 where it forms a projecting bead around the neck. The flanged portion of the sleeve is either hollow throughout its circular extent or is grooved from the rear as shown in Figs. 1 and 5, which accomplishes the same result of forming a seat for the wire 5 which lies in said hollow or groove and projects from it at one point as shown at 6. This wire can be of any suitable nature; but in order to illustrate the preferred form, I have shown it as of triangular cross section giving a cutting edge 7 which facilitates the operation of tearing the sleeve. The other end of the

wire is preferably provided with a stop such as the turn or projection 8, which prevents the wire itself from being drawn through the groove when it is forcibly pulled upon.

5 Any suitable cork 9 is inserted in the neck so as to extend both above and below the line of separation of the sleeve, and above the cork is a filling of cement 11, which is preferably held immovably by a groove, at 10 the mouth of the bottle. The cork is thus rendered inaccessible by the filling, but for additional security I prefer to cover the filling itself with a metallic plate 10, inserted and held in the groove above or in the filling 15 and which affords a convenient means of exhibiting a trade-mark, label or other identifying device for the goods and also positively prevents access to the cork. This plate may be placed in position at the same time as the filling the groove being deep 20 enough to insert it endwise. The bottle can be opened only by rupturing the sleeve 3, which is done by pulling forcibly with the hand or with pliers or any other suitable tool 25 upon the projecting end of the rupturing wire, which tears through the soft metal of the sleeve and separates it into two parts, and, by the same operation, separates the upper part of the bottle neck from the lower. 30 Since the cork is in adhesion to the cement filling, it can be extracted along with the upper part of the neck, and as it projects below said upper part the whole may form a convenient stopper which can be used until the 35 package has been emptied. The act of opening the bottle has so changed its characteristic appearance, from the fact that the neck shows the separation and the remaining part of the sleeve always shows in the transparency of the glass, that it can evidently never be refilled and sold again as an original package. At the same time the preventive means are simple and neat, and have the additional advantage of rupturing no glass in 40 their operation.

A modification of the invention is shown in Fig. 6, in which the same essential ideas as to construction and operation are carried out in a somewhat different way. In this 50 form the sleeve is so constructed as to form in itself the upper portion of the neck of the bottle and may be constructed of metal, rubber, bone, celluloid or other suitable material. The main part of the sleeve 12, corresponds in shape and construction to the upper glass portion 2 of the bottle neck shown 55 in Fig. 1. At its lower end it is reduced in thickness as shown at 13, and the reduced portion is embedded in the glass. The hole 60 or groove in the sleeve is formed above the reduced portion either in the metal of the sleeve itself, or, if the sleeve be made of other material in a separate metal ring associated with such material and contains a rupturing wire seated and projecting in the

same manner as before described. The arrangement of the cork and of the cement filling and plate are the same as in the form first described. The operation is also the same, the rupturing of the sleeve separating 70 it into two parts at about the level of the actual glass bottle neck, and the cork is left protruding from the latter in the manner formerly described.

In Figs. 7 and 8 I have shown special constructions for the sleeves adapted to either the form of Fig. 1 or that of Fig. 4. In Fig. 7 the sleeve is molded or pressed with spirally arranged lugs 14 which are supposed to fit grooves of the same shape in the 80 bottle when molded around them. Fig. 8 shows the sleeve molded with projections 15 for the same purpose. Equivalent holding projections such as circular corrugations may be used for the same purpose. 85

What I claim is:

1. In combination with a glass bottle, a sleeve embedded in the neck thereof, said sleeve having self-contained means for rupturing it and thereby shortening the bottle. 90

2. In combination with a glass bottle, a sleeve of relatively soft material secured in the bottle neck, and an accessible cutting or tearing implement projecting from the sleeve and forming means for rupturing it; whereby after the rupturing a part of the sleeve 95 remains associated with the bottle neck.

3. In combination with the neck of a bottle, a cork seated entirely within the same and below its mouth, an immovable filling 100 above the cork, a sleeve of rupturable material associated with the bottle, and means carried by the sleeve for rupturing it; whereby when the sleeve is ruptured, the upper part of the neck including said filling is 105 removed.

4. In combination with the neck of a bottle having an interior groove at its mouth, a cork seated entirely within the same and below its mouth, an immovable filling above 110 the cork, a plate above the filling, extending with said filling into said groove, a sleeve of rupturable material associated with the bottle neck, and means carried by the sleeve for rupturing it; whereby when the sleeve is 115 ruptured, the upper part of the neck including said filling is removed.

5. In combination with a bottle, a sleeve of rupturable material embedded in the neck, and a wire lying within the sleeve and protruding from it. 120

6. In combination with a bottle, a rupturable sleeve embedded in the neck and a wire formed with a cutting edge, lying within the sleeve and protruding from it. 125

7. In combination with a bottle, a rupturable sleeve, having self contained means for rupturing it and provided with projections for engaging with the material of the bottle.

8. In combination with a bottle, a ruptur- 130

able sleeve, having a reduced portion embedded in the bottle and an enlarged portion externally visible, a tearing wire located in the enlarged portion and protruding from it, whereby said sleeve can be ruptured through the enlarged portion leaving the reduced portion associated with the bottle.

In testimony whereof I affixed my signature in presence of two witnesses, this 4th day of November 1907.

GEORGE GEISENDORFER.
